UNITED STATES PATENT OFFICE.

GEORGE S. SIEBEN, OF OAK BLUFFS, MASSACHUSETTS, ASSIGNOR OF ONE-HALF TO
COLEMAN A. CHURCH, OF OAK BLUFFS, MASSACHUSETTS.

RAZOR.

1,385,280.

Specification of Letters Patent. Patented July 19, 1921.

Application filed September 3, 1920. Serial No. 407,845.

To all whom it may concern:

Be it known that I, GEORGE S. SIEBEN, a citizen of the United States, residing at Oak Bluffs, in the county of Dukes and State of Massachusetts, have invented certain new and useful Improvements in Razors, of which the following is a specification.

This invention relates to improvements in combined hair cutter and safety razor and 10 more specifically an adjustable comb and cutting means which may be easily adjusted for the purpose desired.

One of the objects of my invention is the construction of a novel hair cutter and safety 15 razor including a comb and a razor blade holder adjustable on the comb.

Another and very important object of my invention is the provision of an adjustable hair cutter and safety razor, consisting of 20 few parts, easily assembled and taken apart, accurate and positive in operation and inexpensive to manufacture.

A still further object of this invention resides in an improved comb and razor blade 25 holder adjustable thereon and adapted to hold any type of flat razor blade.

With these objects in view and others which will be suggested as the purpose and 30 nature of my invention are revealed in the specification and drawings, I have shown but one of the various embodiments in the following drawings, where:

Figure 1 is a perspective view of the hair cutter and safety razor assembled.

Fig. 2 is a cross section taken on the line 2-2 of Fig. 1.

Fig. 3 is a detached view of the comb.

Fig. 4 shows a detached razor blade holder.

Fig. 5 shows a razor blade.

Similar numerals in the specification referring to corresponding like parts on the drawing, numeral 1 designates a frame preferably made of thin metal, or the like, having a reduced handle 2 and a comb with spaced teeth 4 of any desirable number. One half of the top portion of the comb is cut away as at 5 to receive a resilient preferably metallic cylindrical razor blade 50 holder 6.

The holder 6 is retained in adjusted position, with respect to the teeth of the comb, in opposed front and rear angular slots 7, 8. The slots 7 are somewhat longer than the 55 forward slots 8 and are cut to provide a

shoulder 9 and fingers 10 for the purpose to be described.

Referring to Fig. 4, it will be seen that the resilient cylindrical blade holder has a slit 10' through which the teeth of the comb 60 may pass, there being opposed slightly offset notches 11, 12 at each end of the holder. The notches in the holder permit the ready insertion of the same in any one of the opposed angular slots 7, 8 of the comb. It 65 should be observed in this connection that it is very essential that the notches 11, 12 be slightly offset so that when the notch 11 is inserted in any one of the angular slots 7, it is necessary to slightly urge the teeth 70 through the notch 12 so that the holder will be seated in its proper position. It is obvious that the holder may be seated in any one of the opposed notches depending on whether a short, long or medium cut is desired. It is further apparent that the flat 75 blade designated 13 is inserted through the slit 10' of the holder and lies on the face of the teeth. Placed in any of its adjusted positions on the comb, the device may be used 80 as a hair cutter or safety razor, as desired.

While I have shown and described a preferred embodiment of my invention and one which I have found to be highly practicable and satisfactory for the uses and purposes 85 desired, I do not wish to limit or restrict myself to the exact details of construction shown, but retain the right to make such changes and alterations as may properly fall within the spirit and scope of the subject 90 matter being claimed.

Having shown and described my invention, what I claim as new and desire to secure by Letters Patent of the United States is:

1. In a combined hair cutter and safety razor, a frame having a handle and a comb, said frame being cut away above the comb, opposed notches forming fingers in the cut away portion of the frame, and a resilient 100 holder and blade adapted to be retained by any of the opposed fingers.

2. In a combined hair cutter and safety razor, a frame having a handle and comb, said frame being cut away above the comb, 105 a resilient holder adjustably mounted in the cut away portion and embracing the comb, and a blade carried by said holder against the comb for the purpose described.

3. In a combined hair cutter and safety 110

razor, a frame comprising a handle and comb, said frame being cut away above the comb and provided with opposed fingers, a resilient holder embracing the comb and having opposed, offset notches for engagement between the fingers, and a blade carried by the holder against the comb, said holder and blade being adjustable with respect to said comb for varying the length of cut.

4. In a combined hair cutter and safety razor, a frame comprising an integral handle and comb, said comb being cut away at its top edge and provided with opposed fin-

gers, a resilient, cylindrical holder and a blade carried thereby and adjustable between the opposed fingers, said blade and comb passing through a longitudinal slit in the holder and securely held thereby, and opposed slightly offset notches in the edges of the holder for engagement beneath the fingers, whereby the holder and blade may be adjustable with respect to the comb for varying the length of cut.

In testimony whereof, I affix my signature hereto.

GEORGE S. SIEBEN.
